CLAIM

The ornamental design for a smoker device, as shown and described.

DESCRIPTION

FIG. 1 is a top perspective view of a first embodiment of a smoker device, showing my new design;

FIG. 2 is a bottom perspective view of a smoker device design showing my new design according to the first embodiment;

FIG. 3 is a front view of FIG. 1;

FIG. 4 is a rear view of FIG. 1;

FIG. 5 is a left view of FIG. 1;

FIG. 6 is a right view of FIG. 1;

FIG. 7 is a top view of FIG. 1;

FIG. 8 is a bottom view of FIG. 1;

FIG. 9 is a top perspective view of a second embodiment of a smoker device, showing my new design;

FIG. 10 is a bottom perspective view of a smoker device design showing my new design according to the second embodiment;

FIG. 11 is a front view of FIG. 9;

FIG. 12 is a rear view of FIG. 9;

FIG. 13 is a left view of FIG. 9;

FIG. 14 is a right view of FIG. 9;

FIG. 15 is a top view of FIG. 9; and,

FIG. 16 is a bottom view of FIG. 9.

The broken lines in the drawings depict portions of the smoker device that form no part of the claimed design.
